UNITED STATES PATENT OFFICE.

FRANCIS G. DIETZ, OF NEW YORK, N. Y.

DESIGN FOR A GARMENT-SUPPORTER.

SPECIFICATION forming part of Design No. 35,548, dated January 7, 1902.

Application filed December 5, 1901. Serial No. 84,836. Term of patent 14 years.

To all whom it may concern:

Be it known that I, FRANCIS G. DIETZ, a citizen of the United States, residing at New York, in the county of New York and State 5 of New York, have invented and produced a certain new and original Design for Garment-Supporters, of which the following is a specification.

My invention consists in the design for a 10 garment-supporter, substantially as shown in the accompanying drawings, in which—

Figure 1 is a perspective view of a garment-supporter made according to my design. Fig. 2 is a rear elevation of the same, and Fig. 3 15 is a top plan view.

The base 1 of the supporter made according to my design is bent at a point adjacent to its center to form the back 2 and the front 3, the said back and front being connected at 20 the bend referred to by a substantially circular web 4. The back 2 is provided at its center with a circular opening 5 and has adjacent to its side edge and upper and lower ends the elongated openings 6. The front 3 25 has the side edge thereof bent inwardly to form a lip or flange 7, and said front has se-

cured to it a hook 8. The said hook is connected to the front 3 at a point adjacent to the center of the latter and extends through an opening therein opposite the opening 5 in 30 the back 2. The projecting end of said hook on the inner side of the front 3 is upset, as shown, and forms a plurality of teeth 9 opposite the opening 5. From its point of attachment with the front 3 the hook 8 is bent downwardly to form with said front 3 a downwardly-facing loop 10 and is then bent upwardly to form an upwardly-facing loop 11. The extreme outer end of said hook extends downwardly to form a downwardly-facing loop 12. 35 40

Having now described my invention, what I claim as new is—

The design for a garment-supporter, substantially as shown and described.

In testimony whereof I have hereunto set 45 my hand in presence of two subscribing witnesses.

FRANCIS G. DIETZ.
